UNITED STATES PATENT OFFICE

MILLINS W. PROUTY, OF BRAINTREE, MASSACHUSETTS, ASSIGNOR TO ALBERT L. BERRY LEATHER COMPANY, OF BOSTON, MASSACHUSETTS, A CORPORATION OF MASSACHUSETTS

DESIGN FOR A SHOE INSOLE MATERIAL OR SIMILAR ARTICLE

Application filed February 9, 1933. Serial No. 47,169. Term of patent 14 years.

To all whom it may concern:

Be it known that I, MILLINS W. PROUTY, a citizen of the United States, residing at Braintree, in the county of Norfolk and State of Massachusetts, have invented a new, original, and ornamental Design for a Shoe Insole Material or Similar Article, of which the following is a specification, reference being had to the accompanying drawing, forming part thereof.

The figure is a fragment of an insole for a shoe showing my new design as applied thereto.

The horizontal and vertical elements resembling lettering are among the essential features of the design; and it is the visual appearance of the lettering which is essential rather than the particular meaning of any lettering thus arranged.

I claim:

The ornamental design for a shoe insole material or similar article, as shown and described.

MILLINS W. PROUTY.
